[57] CLAIM

The ornamental design for the billiard trophy and cue chalk container, as shown and described.

DESCRIPTION

FIG. 1 is a perspective view of a billiard trophy and cue chalk container showing my new design;

FIG. 2 is a right side elevation view thereof, the opposite side being a mirror image;

FIG. 3 is a top plan view thereof; and,

FIG. 4 is a bottom plan view thereof.

The broken line description is for illustrative purpose only and forms no part of the claimed design.
